UNITED STATES PATENT OFFICE.

JESSE J. HEAP, OF NYACK, NEW YORK, ASSIGNOR TO UNION SPECIAL MACHINE COMPANY, OF CHICAGO, ILLINOIS, A CORPORATION OF ILLINOIS.

OVERSEAMING MACHINE.

Application filed May 4, 1922. Serial No. 558,363.

To all whom it may concern:

Be it known that I, JESSE J. HEAP, a citizen of the United States, residing at Nyack, in the county of Rockland, State of New

5 York, have invented certain new and useful Improvements in Overseaming Machines, of which the following is a description, reference being had to the accompanying drawing and to the figures of reference marked 10 thereon.

The invention relates to new and useful improvements in over-seaming machines, and more particularly to an over-seaming machine having a horizontally disposed 15 needle for over-seaming fabric sections placed in a vertical position.

An object of the invention is to provide a machine of the above type with means for turning over the edge portions of the fabric 20 sections so that the over-seaming stitches will stitch down said over-turned portions.

A further object of the invention is to provide a machine of the above type wherein the edge portions are both turned over on to 25 one face of the fabric sections.

A still further object of the invention is to provide a machine of the above type with a supporting means over which the edge 30 portions may be turned, and means for turning the edge portions over the supporting means, said supporting and turning means being disposed so that the over-seaming stitches will encircle the over-turned edge portions of the fabric sections.

A still further object of the invention is to provide a machine of the above type with a stitch finger which is located above the edge supporting and turning portions. 35

A still further object of the invention is to provide a machine of the above type with means for uncurling the edge portions of the fabric sections prior to the feeding of the same to the edge supporting and turning devices.

40 These and other objects will in part be obvious and will in part be hereinafter more fully disclosed.

In the drawings which show by way of illustration one embodiment of the invention—

Figure 1 is a side view of a portion of a machine embodying my improvements;

Fig. 2 is a front view of the same;

Fig. 3 is a view partly in section and partly in plan showing the feed cups, a por-

tion of the stitch finger, the needle and the looper, the edge turning devices, and the uncurling devices and their relation to each other;

Fig. 4 is a view showing partly in section and partly in plan, the needle and the looper, the uncurling devices, and the edge supporting and turning devices, and

Fig. 5 is a perspective view showing two fabric sections and the devices for supporting and turning the edge portions of the fabric sections.

The machine to which my invention is applied is of the type known in the art as a cup-feed machine, and I prefer to use a 70 machine such as disclosed in the patent granted to Lansing Onderdonk, September 5, 1916, No. 1,197,055, to which patent reference may be had for a more thorough disclosure of the over-seaming mechanism.

The machine is especially adapted for uniting the edge portions of chiffon hose or the like. The hose are preferably knit on a circular knitting machine, and are then split in order to facilitate the applying of embroidery thereto, after which the split portions of the hose are connected by a seam. The present machine is provided with means for uncurling these edge portions and directing the same to the stitching mechanism with the edge portions side by side and in vertical position. Between the uncurling devices and the stitching mechanism, is my improved means for turning the edge portions of the fabric sections. 85

These devices consist of a supporting member over which the edge portions are turned on to one face of one of the fabric sections. A turning member is also provided for folding over or turning over said edge portions. The supporting and turning means for the edge portions of the fabric sections is below the stitch finger and so disposed relative to the needle that the overseaming mechanism places the over-seaming stitches about the inturned portions. My improved means can therefore be used for stitching these light materials and with an over seam of the usual width without any liability of the stitches pulling out.

Referring more in detail to the drawings, I have shown my invention as applied to a sewing machine having a machine framework 1 carrying a bracket 2 in which is mounted an intermittently rotatable shaft

carrying a feed wheel 3. The machine is also provided with a bracket 4 in which is mounted a rotatable shaft carrying a feed wheel 5. These feed wheels 3 and 5 cooperate in feeding the material to the stitching mechanism, said material being held in a vertical position while it is being stitched by said feed wheels. The stitching mechanism includes a needle 6 and a thread carrying looper 7. The looper is of the well known type used on cup-feed machines and is preferably operated by a mechanism such as disclosed in the Onderdonk patent above referred to. The looper therefore moves in 10 to the needle thread loop on one side of the fabric sections and then across to the other side of the fabric sections where it is so positioned that the needle will enter the looper thread loop, and then forms an over-seam about the edges of the fabric sections. In Fig. 5 of the drawings, the two fabric sections to be united are indicated at f and f' . The needle threads are indicated at n and the looper threads at l . The two fabric sections f and f' first pass through an uncurling device which consists of a central plate 8, on one side of which is an uncurling member 9 and on the other side of which is an uncurling member 10. The uncurling member 9 is pivoted at 11 and a spring 12 normally presses the same against the central plate 8. 13 is a limiting stop for the uncurling member 9. The uncurling member 10 is pivoted at 14 and a spring 15 normally forces said uncurling member against the plate 8, and a stop 16 is provided for said uncurling member 10. As clearly shown in Fig. 4, the two fabric sections f and f' pass between the respective uncurling members and the plate 8 and thus the edges are uncircled, as they approach the stitching mechanism. Rigidly secured to the uncurling member 9 is a supporting finger or rod 17. Said supporting finger is provided with a loop portion 18 adapted to receive a screw 19 whereby said supporting finger is secured to the uncurling member 9. Said supporting finger extends forwardly and its extreme forward end 20 is parallel with the line of feed 40 and of such a height that the edge portions of the fabric sections may be turned over said supporting finger. The edge portions are turned over said supporting finger by means of a rod 21. This rod 21 has a loop portion 22 and a screw 23 passing through said loop portion 22 secures the same to the uncurling member 10. The rod 21 is provided with a bent portion 23' at its forward end which extends over the supporting finger 45 17 and is so shaped and disposed relative to said supporting finger as to roll or turn the two edge portions of the fabric sections f and f' over the supporting finger 17, as clearly shown in Figures 4 and 5. These supporting and turning devices are located

beneath the stitch finger 24 over which the over-seaming stitches are formed, and they are also located between the needle path and the uncurling devices, and are furthermore so disposed relative to the feed wheels that 70 the turned over edge portions will be encircled by the overseaming stitches. The needle passes through the fabric sections adjacent the edges of the turned over edge portions, and the looper thread is carried 75 over the folded edge portions thus encircling the inturned portions of the fabric. This as above noted, makes a very strong and durable seam, and enables very light material, such as chiffon, to be stitched and 80 sections of the same joined in a very slightly and durable manner.

It is obvious that minor changes in the details of construction and the arrangement of the parts may be made without departing 85 from the spirit of the invention as set forth in the appended claims.

Having thus described the invention, what I claim as new and desire to secure by Letters-Patent, is—

1. The combination of over-seaming mechanism, means for supporting and feeding fabric sections placed side by side in a vertical position, and means for turning over the edge portions of the fabric sections 95 on to the face of one of the fabric sections prior to the stitching of the same whereby said over-turned edge portions are surrounded and secured by the over-seaming stitches.

2. The combination of overseaming mechanism, means for supporting and feeding fabric sections placed side by side in a vertical position, a stitch finger, an uncurling device, and means located between the uncurling device and the stitch finger for turning over the edge portions of the fabric sections 105 on to the face of one of the fabric sections prior to the stitching of the same, whereby said overturned edge portions are surrounded by the stitches laid over the 110 stitch finger and secured thereby.

3. The combination of over-seaming mechanism, means for supporting and feeding fabric sections placed side by side in a vertical position, a stitch finger, an uncurling device, and means located between the uncurling device and the over-seaming mechanism for turning over the edge portions of the fabric sections prior to the stitching of the same, said means for turning over the edge portions of the fabric sections being located beneath the stitch finger and so disposed as to turn over the edge portions of the fabric sections within the limits of the 115 over-seaming stitches whereby the over-seaming stitches cover the same.

4. The combination of over-seaming mechanism, feed wheels for supporting and feeding fabric sections in a vertical position, means for uncurling the fabric sections and 120

- 5 directing the same to the feed wheels, devices located between the uncurling means and the over-seaming mechanism for turning over the edge portions of the fabric sections 50 on to one face of one of said fabric sections.
- 5 6. The combination of over-seaming mechanism, feed wheels for supporting and feeding fabric sections in a vertical position, means for uncurling the fabric sections and 10 directing the same to the feed wheels, devices located between the uncurling means and the overseaming mechanism for turning over the edge portions of the fabric sections on to one face of one of said fabric sections,
- 15 7. The combination of over-seaming mechanism, feed wheels for supporting and feeding fabric sections in a vertical position, said devices being so arranged as to turn over the edge portions within the limits of the over-seaming stitches whereby said over-turned edge portions are covered by the 15 seaming stitches.
- 20 8. The combination of over-seaming mechanism, feed wheels for supporting and feeding fabric sections in a vertical position, a supporting finger located alongside of one of said fabric sections, means associated there- 25 with for turning the edge portions of the fabric sections over said supporting finger, said supporting finger being so positioned that the over-turned edge portions are covered by the over-seaming stitches.
- 25 9. The combination of over-seaming mechanism, means for supporting and feeding fabric sections in a vertical position, uncurling means for uncurling the edges of the fabric sections, and devices located be- 30 tween the uncurling means and the over-seaming mechanism for over-turning the edge portions of the fabric sections on to one face of the fabric sections prior to the stitching of the same.
- 35 10. The combination of over-seaming mechanism, means for supporting and feeding fabric sections in a vertical position, uncurling means for uncurling the edges of the fabric sections, and devices located be- 35 tween the uncurling means and the over-seaming mechanism for over-turning the

edge portions of the fabric sections on to one face of the fabric sections prior to the stitching of the same, said over-turning means being disposed relative to the over-seaming mechanism so that the over-turned portions are within the limits of the over-seaming stitches and covered thereby.

9. The combination of over-seaming mechanism, feed wheels, a central supporting plate, an uncurling member at each side of said plate for uncurling the edges of the fabric sections to be stitched, a supporting finger carried by one of said uncurling members and having the supporting end thereof located between the uncurling member and the stitching mechanism, a turning rod carried by the other uncurling member and having its fabric turning end disposed between the uncurling members and the stitching mechanism, and relative to the supporting finger so as to turn over the edge portions of the fabric sections on to said supporting finger.

10. The combination of over-seaming mechanism, feed wheels, a central supporting plate, an uncurling member at each side of said plate for uncurling the edges of the fabric sections to be stitched, a supporting finger carried by one of said uncurling members and having the supporting end thereof located between the uncurling member and the stitching mechanism, a turning rod carried by the other uncurling member and having its fabric turning end disposed between the uncurling members and the stitching mechanism, and relative to the supporting finger so as to turn over the edge portions of the fabric sections on to said supporting finger, said supporting finger being disposed relative to the over-seaming mechanism so that the edge portions are over-turned within the limits of the over-seaming stitches and covered thereby.

In testimony whereof, I affix my signature.

JESSE J. HEAP.
